C. S. Tingle,
INVENTOR:

By W. J. Fitzgerald
Attorney

UNITED STATES PATENT OFFICE.

CHESTER S. TINGLE, OF HORTONVILLE, INDIANA.

WEATHER-STRIP.

SPECIFICATION forming part of Letters Patent No. 445,459, dated January 27, 1891.

Application filed July 15, 1890. Serial No. 358,801. (No model.)

To all whom it may concern:

Be it known that I, CHESTER S. TINGLE, a citizen of the United States, residing at Hortonville, in the county of Hamilton and State 5 of Indiana, have invented certain new and useful Improvements in Weather-Strips; and I do hereby declare the following to be a full, clear, and exact description of the invention, such as will enable others skilled in the art 10 to which it appertains to make and use the same.

My invention relates to new and useful improvements in weather-strips, the object of which is to protect the floor or carpet from 15 being saturated with water that may be driven under the door and also to exclude dust, as will be hereinafter fully described and claimed, reference being had to the accompanying drawings, in which—

20 Figure 1 is a perspective view of my weather-strip removed from its operative position. Fig. 2 is a transverse section of the weather-strip and the spiral spring connected thereto, and also shows a part of the door and thresh- 25 old.

Referring to the several parts of my invention by letter, A is the body thereof, which is formed of any preferred sheet metal of sufficient length to reach from one side of the door 30 to the other and having its ends cut to conform to the shape of the frame and casing of the door, the blade end a of which is adapted to pass entirely under the door and reaches slightly past the outer edge of the carpet-strip, 35 while the inner and longer edge a'' thereof is bent upward at right angles to the blade portion a, the object of which is to present a barrier against the admission of water and dust. The extremities a³ of the edge a'' are bent in 40 at right angles, so that their ends will come against the inner side of the door, and the ends of the weather-strip are thus closed to prevent any water that may beat under the door from running on the carpet and into the room. 45 The corners of the blade part a of the device are cut away at a' to adapt them to fit the door-casing, as will be readily understood.

My weather-strip is not secured permanently to the door, but is adapted to be at-

tached thereto temporarily by means of the 50 spiral spring B, one end of which is connected to the middle of the portion a'', while the other end reaches upwardly and terminates in the hook that is adapted to engage a staple C secured in the door, as shown. 55

In operation my weather-strip is placed in position by inserting the blade portion a under the door and forcing the same inward until its edge shall reach slightly past the weather-strip, when the upper end of the 60 spiral spring, which is provided with a suitable hook b, is secured to the staple C, and when so arranged the tension of the spring will hold the weather-strip in position and thus prevent water and dust from being driven 65 under the door, as it will be seen that the inner section a'' will catch and hold the same, if any should pass under the door. After the storm is over, or when the necessity of the weather-strip is no longer felt, the upper end 70 of the spiral spring is disengaged from connection with the staple C and the entire weather-strip removed until again needed, when it can be readily replaced, as explained.

Having thus described my invention, what 75 I claim as new, and desire to secure by Letters Patent, is—

1. A removable weather-strip consisting of the body A, having the sections a a'', the ends of which are cut to conform to the shape of 80 the frame and casing of the door, the spiral spring secured to the middle of the section a'' and adapted to reach upward to engage with the staple C, substantially as set forth.

2. The combination, with the door and its 85 casing, of a removable weather-strip consisting of the body A, provided with the sections a a'', the spiral spring reaching from the middle of the latter to the staple C and adapted to hold the weather-strip temporarily in position, substantially as described, and for the 90 purpose named.

In testimony whereof I affix my signature in presence of two witnesses.

CHESTER S. TINGLE.

Witnesses:

JOHN A. ALDRED,
HENRY L. BOYD.
